UNITED STATES PATENT OFFICE.

EDWIN A. PETERSON, OF MADISON, WISCONSIN, ASSIGNOR TO UNDERWOOD TYPE-WRITER COMPANY, OF NEW YORK, N. Y., A CORPORATION OF DELAWARE.

TYPEWRITING MACHINE.

Application filed May 20, 1922. Serial No. 562,974.

To all whom it may concern:

Be it known that I, EDWIN A. PETERSON, a citizen of the United States, residing in Madison, in the county of Dane and State 5 of Wisconsin, have invented certain new and useful Improvements in Typewriting Machines, of which the following is a specification.

This invention relates to releasable or 10 disengageable paper-engaging or paper-guiding devices of a typewriting machine, and relates more particularly to the curved paper-guiding fingers which usually extend downwardly at the front of the platen, for 15 guiding a work-sheet upwardly around the platen, after the leading edge of the work-sheet has advanced beyond the usual paper-guiding devices below the platen.

Commonly, such paper-guiding fingers, 20 which are usually two in number, may be swung upwardly away from the platen, and are also adjustable along the platen; and, in order to enable these movements of the paper-guiding fingers, each finger has 25 an arm which is pivoted to swing upon and also mounted to slide along a rod which extends parallel to the platen and is fixed at its ends in the end walls of the platen-frame, usually rearwardly from the top of 30 the platen. For releasably or disengageably holding the paper-guiding finger at its effective position and for yieldingly pressing it towards the platen, the supporting arm of the paper-guiding finger carries 35 a small roll and a spring for pressing the roll into a groove which extends along the rod throughout its length. When it is desired to withdraw the paper-guiding finger from the platen, it may be swung upwardly 40 and rearwardly around the rod, the spring-pressed roll being then forced, by cam action, out of the groove and upon the cylindrical outer surface of the rod, upon which the roll may move around the rod, 45 whereupon the friction of the spring-pressed roll upon the rod will hold the paper-guiding finger at whatever elevated position to which it may be swung. When it is desired to adjust the paper-guiding finger 50 along the platen, such adjustment is usually made with the finger at its raised position, so that the work-sheets on the platen will not be disturbed, and also because it is often desired to adjust the paper-guiding finger past a type-guide and other devices 55

which are commonly mounted in front of and near to the platen at about the printing line, below which the paper-guiding fingers usually extend. When the paper-guiding finger is swung upwardly, obviously 60 its spring-pressed roll will be pressed by its spring more strongly against the finger-supporting rod than when the roll is in the groove, so that, when the paper-guiding finger is at its elevated position, the small 65 roll is pressed so strongly against the cylindrical surface of the finger-supporting rod that there is considerable frictional resistance against sliding the finger-carrying arm along the rod, the spring-pressed roll 70 having a strong tendency to bind upon the rod, so as to prevent the finger-carrying arm from sliding freely thereon, thereby interfering with the adjustment of the lifted paper-guiding finger along the platen. 75

In order to overcome this objection, according to the present invention, the finger-supporting rod is formed with a relief-groove extending throughout the length of the rod at the proper place, so that, when 80 the paper-guiding finger is raised from the platen to the desired position, the small spring-pressed roll will enter the relief-groove and thereby relieve the tension of its spring, so that the finger-carrying arm may 85 slide freely along the rod, thereby enabling the elevated paper-guiding finger to be adjusted along the platen without any difficulty.

Other features and advantages will here- 90 inafter appear.

In the accompanying drawings,

Figure 1 illustrates an embodiment of the present invention in a typewriting machine, and is a largely diagrammatic front-to-rear vertical section, with parts in elevation, showing a platen-frame, with associated parts, including a paper-guiding finger at its effective position.

Figure 2 is a similar view, but with the 100 paper-guiding finger raised away from the platen, so as to be freely adjusted along the platen, by reason of the present invention.

Figure 3 is a front elevation, substantially as viewed from the right of Figure 1, and shows two paper-guiding fingers at their paper-guiding positions at the front of the platen.

In order clearly to understand the present 110

invention, the usual associated parts of the typewriting machine, which are involved in the present invention and co-operate therewith, will be first described; the typewriting machine, parts of which are shown in the drawings, being a usual or standard Underwood machine. In this machine, a revoluble platen 1 is journaled by means of its axle 2, in the end walls 3 of a usual platen-frame including a lower tie-rod 4, the platen-frame carrying the usual releasable front and rear feed-rolls 5 and 6 to run upon the bottom of the platen. The printing point at the front of the platen is indicated in Figure 1 by the lower-case type carried by the raised type-head 6^a.

Usual right and left curved paper-guiding fingers 7 extend from above downwardly at the front of the platen beyond the printing line, each finger 7 being provided at its upper part with a usual small pressure-roll 8, and each finger 7 being carried by an arm 9, which is connected thereto, at the forward end of the arm and at the upper end of the finger, by means of a transverse intermediate portion 10 provided with an upstanding forwardly-curved finger-piece 11. At their rear ends, the forwardly-extending finger-carrying arms 9 are mounted to swing or rock upon, and also to slide along, a finger-supporting rod 12, which extends parallel to the platen 1 at the rear of the top of the platen, and at its ends is firmly fixed in the end walls 3 of the platen-frame. Each arm 9 of the corresponding paper-guiding finger 7 is pivotally and slidably mounted upon the transverse rod 12 by means of an inwardly-turned U-shaped portion comprising an outer side-part 13, forming a continuation of the arm 9, and an inner side-part 14 spaced inwardly from the outer side-part 13 and connected thereto by means of a transverse connecting part or member 15. The construction of the two paper-guiding devices, including the fingers 7, is the same except that one is right-hand and the other is left-hand, as will be clear from the drawings.

Means are provided for releasably or disengageably holding the paper-guiding fingers 7 in proximity to the front of the platen 1, to press against and guide the side margins of a work-sheet on the platen; comprising, for each paper-guiding finger 7, a small rod-like roll 16 having reduced ends 17, which are guided in small slots 18 provided in the respective sides 13 and 14 of the U-shaped part of the finger-carrying arm 9, the roll 16 being yieldingly pressed towards the finger-supporting rod 12 by means of a curved leaf-spring 19 having outwardly-turned straight ends 20 to press against the ends of the roll 16, and having small down-turned ears or lugs 21 engaging at opposite sides of the transverse con-

necting member 15, to hold the spring in place. The ends 20 of the spring 19 are curved to fit the roll 16, as shown in Figure 2. The spring 19 presses the small roll 16 into a nearly semi-circular holding-groove 22 in the rod 12, and extending along this rod throughout its length between the end walls 3 of the platen frame; in the construction shown in the drawings, this roll-receiving groove 22 being shown in the lower side of the rod 12. In the effective or paper-guiding position of the fingers 7 shown in Figures 1 and 3 of the drawings, the spring-pressed roll 16 is engaged in the groove 22, so as yieldingly to press the fingers 7 towards the platen. When the small roll 16 is in the groove 22, it forms a spline. When a paper-guiding finger 7 is raised, or swung upwardly from the platen 1, the small finger-holding roll or spline 16, which also forms a detent, will be cammed out of the holding groove 22, and will ride upon the cylindrically-curved outer surface 23 of the rod 12; and the pressure of the roll 16 against this outer surface 23 of the rod 12 will be greater than the pressure of this roll against the bottom of the holding-groove 22, by reason of the increased tension of the spring 19. The construction so far described is the same as has heretofore been commonly employed in the Underwood typewriting machine.

According to the present invention a relief-groove 24 is cut or otherwise formed along the rod 12, and extends throughout the length of this rod between the platen-frame end walls 3. This relief-groove 24 is provided at the proper place, in circumferentially-spaced relation to the holding-groove 22, so that the relief-groove 24 will receive the small detent-roll or spline 16 when the paper-guiding finger 7 is swung to the desired raised position, as shown in Figure 2. In the construction shown in the drawings, the relief-groove 24 is provided in the upper portion of the front of the rod 12. The relief-groove 24 relieves the tension of the spring 19, so that the small roll 16 will be pressed with much less force against the bottom of the relief-groove 24 than it was pressed against the cylindrically-curved outer surface 23 of the rod 12. This decreased pressure of the detent-roll 16 against the rod 12 greatly lessens the friction of sliding the spline-forming detent-roll 16 along the rod 12 when this roll is in the relief-groove 24, and avoids or eliminates the tendency of the roll 16 to bind upon the rod 12, whereby the arm 9 of the finger 7 may be easily slid or slipped along the rod 12, thereby enabling the paper-guiding finger 7 to be freely adjusted along the platen 1, when the paper-guiding finger 7 is swung to its elevated position shown in Figure 2. This relief of pressure of the spring-pressed detent-

roll 16 against the finger-supporting rod 12 similarly applies to both of the paper-guiding fingers 7, so that either of these fingers, in its elevated position, may be freely adjusted along the platen 1, without binding or undue friction upon the rod 12. In adjusting the paper-guiding finger 7 along the platen 1, the small detent-roll 16 acts as a spline in the relief-groove 24 to guide the fingers 7 at the raised position thereof shown in Figure 2.

The somewhat less than semi-circular holding-groove 22 snugly receives the small detent-roll 16 and is of the proper depth, so that the pressure of the roll 16 in this groove will be effective to hold the paper-guiding finger 7 and its pressure-roll 8 in proximity to the platen 1, as shown in Figures 1 and 3. However, in order to afford maximum relief to the spring 19, so as correspondingly to decrease to a maximum extent the pressure of the roll 16 in the relief-groove 24, this relief-groove may be of somewhat greater depth than the holding-groove 22, as well as somewhat wider, and may be provided with sloping sides to enable the small detent-roll 16 to become disengaged from or ride out of the relief-groove 24 when it is desired to return the paper-guiding finger 7 from its elevated position shown in Figure 2, to its effective position shown in Figures 1 and 3. The above-noted differences between the holding-groove 22 and the relief-groove 24 will be evident by an inspection of Figures 1 and 2.

Variations may be resorted to within the scope of the invention, and portions of the improvements may be used without others.

Having thus described my invention, I claim:

1. In a typewriting machine, in combination, a rod fixed upon and extending transversely of the machine, a paper-engaging device mounted to be swung upon the rod to or from effective position, and also slidable along the rod for adjusting said device to different positions transversely of the machine, said rod being cut away longitudinally thereof to provide a holding-portion, and a spring-pressed detent carried by said device to be pressed against said holding-portion of the rod for yieldingly holding said device at its effective position, said rod also being cut away longitudinally thereof to provide a relief-portion to receive said spring-pressed detent for relieving the pressure of said detent against the rod when said device is swung to ineffective position, so that said device may slide freely along the rod to different positions of adjustment transversely of the machine.

2. In a typewriting machine, in combination, a rod fixed upon and extending transversely of the machine, a paper-engaging device mounted to be swung upon the rod to

or from effective position and also slidable along the rod for adjusting said device to different positions transversely of the machine, said rod being provided with a holding-groove extending longitudinally thereof and also being provided with a relief-groove extending longitudinally thereof, and a spring-pressed detent carried by said device and releasably engageable in said holding-groove for yieldingly holding said device

at its effective position, and in the ineffective position of said device said detent being releasably engageable in said relief-groove to relieve the pressure of said spring-pressed detent against the rod, so that said device may slide freely along the rod to different positions of adjustment transversely of the machine.

3. In a typewriting machine, the combination with a platen-frame and a revoluble platen journaled therein, of a rod parallel to the platen and fixed at its ends to the platen-frame, a paper-guiding device to co-operate with the platen and pivoted on said rod to enable the paper-guiding device to be swung away from the platen and slideable on said rod to adjust the paper-guiding device along the platen, said rod being cut away longitudinally thereof, and a detent-member carried by said device to be spring-pressed against said rod where it is cut away for holding the paper-guiding device in co-operative relation with the platen, said rod also being cut away longitudinally thereof at another place on its circumference to relieve the pressure of said spring-pressed detent-member against the rod when the paper-guiding device is swung away from the platen, so that the paper-guiding device may be freely adjusted along the platen.

4. In a typewriting machine, the combination with a platen-frame and a revoluble platen journaled therein, of a rod parallel to the platen and fixed at its ends to the platen-frame, a paper-guiding device to co-operate with the platen and pivoted on the rod to enable the paper-guiding device to be swung away from the platen and slideable on the rod for adjusting the paper-guiding device along the platen, said rod having a groove extending lengthwise thereof, and a roll carried by said device and spring-pressed into said groove for holding the paper-guiding device in proximity to the platen, said rod having another groove along its length at another point circumferentially thereof to receive said spring-pressed roll for relieving the pressure of said roll against the rod when the paper-guiding device is swung away from the platen, so that the paper-guiding device may be freely adjusted along the platen.

5. In a typewriting machine, the combination with a platen-frame and a revoluble

platens journaled therein, of a rod parallel to the platen and fixed at its ends to the platen-frame, a paper-guiding device to co-operate with the platen and pivoted on the 5 rod to enable the paper-guiding device to be swung away from the platen and slideable on the rod for adjusting the paper-guiding device along the platen, said rod having a holding-groove extending lengthwise thereof, and a roll carried by said device and 10 spring-pressed into said groove for holding the paper-guiding device in proximity to the platen, said rod also having a relief-groove along its length to receive said 15 spring-pressed roll for relieving the pressure of said roll against the rod when the paper-guiding device is swung away from the platen, so that the paper-guiding device may be freely adjusted along the platen, 20 said relief-groove being of greater depth than said holding-groove, whereby when said spring-pressed roll is in said holding-groove it will be effective to hold said device in proximity to the platen, and when 25 said spring-pressed roll is in said relief-groove maximum relief of pressure of said roll against said rod will be afforded.

6. In a typewriting machine, the combination with a platen-frame and a revolvable 30 platen journaled therein, of a rod parallel to the platen above and to the rear thereof

and fixed at its ends to the platen-frame, a curved paper-guiding finger extending down in front of the platen to co-operate therewith and having an arm pivoted on 35 the rod to enable the paper-guiding finger to be swung upwardly away from the platen, said arm being slideable along the rod to adjust the paper-guiding finger along the platen, said rod having a holding-groove 40 extending lengthwise thereof, and a spring-pressed roll carried by said arm to engage in said groove for holding the paper-guiding finger down in proximity to the platen, said rod having a relief-groove 45 extending lengthwise thereof in circumferentially-spaced relation to said holding-groove for receiving said spring-pressed roll when the paper-guiding finger is swung upwardly away from the platen, to relieve 50 the pressure on said rod of said spring-pressed roll, so that said arm may freely slide on said rod for freely adjusting the paper-guiding finger along the platen when the paper-guiding finger is lifted away 55 from the platen to enable said spring-pressed roll to enter said relief-groove.

EDWIN A. PETERSON.
